(57) **CLAIM**

The ornamental design for an induction trash can, as shown and as described.

DESCRIPTION

FIG. 1 is a perspective view showing my new design.

FIG. 2 is a front view of FIG. 1.

FIG. 3 is a rear view of FIG. 1.

FIG. 4 is a left end view of FIG. 1.

FIG. 5 is a right end view of FIG. 1.

FIG. 6 is a top view of FIG. 1; and,

FIG. 7 is a bottom view of FIG. 1.

The lighter grey area on the center of the bottom of the trash can in FIG. 7 is to show portions which are not part of the claimed design.

1 Claim, 6 Drawing Sheets

FIG. 1

FIG. 2

FIG. 3

FIG. 4

FIG. 5

FIG. 6
